(57) **CLAIM**

The ornamental design for a loudspeaker, as shown and described.

DESCRIPTION

FIG. 1 is a front view of a loudspeaker, showing a first illumination in the sequence showing the new design; FIG. 2 is a second illumination thereof; FIG. 3 is a third illumination thereof; FIG. 4 is a fourth illumination thereof; FIG. 5 is a fifth illumination thereof; FIG. 6 is a sixth illumination thereof; and, FIG. 7 is a seventh illumination thereof.

The appearance of the animated illuminations sequentially transitions between the illuminations shown in FIGS. 1-7. The process or period in which one illumination transitions to another forms no part of the claimed design.

The dash-dot broken lines represent the boundaries of the claimed design and form no part of the claimed design. The evenly spaced broken lines in the figures illustrate portions of the loudspeaker and form no part of the claimed design. The lightened gray areas outside of the two larger dash-dot circles, within the two smaller dash-dot circles, and within the evenly spaced broken lines of the center rectangle, illustrate environmental subject matter that forms no part of the claimed design. None of the broken lines forms any part of the claimed design.
